UNITED STATES PATENT OFFICE

NILS LOFQUIST, OF DALTON, MASSACHUSETTS

DESIGN FOR A REVOLVING TOY BELL

Application filed November 26, 1932. Serial No. 46,185. Term of patent 14 years.

To all whom it may concern:

Be it known that I, NILS LOFQUIST, a citizen of Sweden, residing at Dalton, in the county of Berkshire and State of Massachusetts, have invented a new, original, and ornamental Design for a Revolving Toy Bell, of which the following is a specification, reference being had to the accompanying drawing, forming a part thereof.

Figure 1 is a side elevational view of a revolving toy bell embodying my design.

Figure 2 is a plan view.

I claim:

The ornamental design for a revolving toy bell as shown.

NILS LOFQUIST.
